Henry W. Winter

UNITED STATES PATENT OFFICE.

HENRY W. WINTER, OF METHUEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STAMPING-MACHINE.

1,292,201.

Specification of Letters Patent. Patented Jan. 21, 1919.

Application filed August 9, 1915. Serial No. 44,472.

To all whom it may concern:

Be it known that I, HENRY W. WINTER, a citizen of the United States, residing at Methuen, in the county of Essex and State of Massachusetts, have invented certain Improvements in Stamping-Machines, of which the following description, in connection with the accompanying drawings, is a specification, like reference characters on the drawings indicating like parts in the several figures.

This invention relates to machines for stamping sheet material such, for example, as upper leather for boots and shoes.

An object of the invention is to provide a machine having a large number of stamping dies readily accessible and easily adjustable to present in stamping position the various characters required. In marking parts of shoe uppers, the manufacturer often desires to impress a part with a case number comprising as many as six digits, a size and width indication, comprising five characters including a half-size symbol, and a match mark of two symbols. Of these thirteen symbols, the case number requires to be changed only at relatively long intervals while the others must be changed much more frequently. An important feature of the invention, accordingly, consists in a marking machine having two series of adjustable stamping dies, each die of one series being provided with a hand operated controlling device by which the die may be readily set, while the dies of the other series are adjustable but are not provided with adjusting devices. Such construction renders it possible to provide a marking machine with the large number of dies necessary for all possible uses while, at the same time, convenient provision is made for the adjustment of those dies which require adjustment most frequently.

The present invention, in one of its aspects, contemplates the provision of a marking machine equipped with heated dies, and certain features of the invention are designed to afford convenient means for heating such dies and for controlling the adjustments of the heated dies. As herein shown, a series of thin disks are provided with die bearing teeth upon the periphery of each and these disks are arranged side by side upon a hollow journal member which incloses an elec-

tric heating unit. Adjusting means including a pinion arranged in mesh with each disk serve for turning the disks to present one or another die in stamping position. This construction affords a compact arrangement of the dies and permits a large number of symbols to be impressed upon the work within a short space.

Other features of the invention consist in improved mechanism for controlling and adjusting the point of nearest approach of the stamping head and the work table and for permitting one to yield with respect to the other to accommodate work of varying thickness.

These and other features of the invention will be best understood and appreciated from the following description of a preferred embodiment thereof selected for purposes of illustration and shown in the accompanying drawings in which—

Figure 1 is a view in perspective of the machine;

Fig. 2 is a sectional view of the machine; Figs. 3 and 4 are detail views in perspective;

Fig. 5 shows a shoe part which has been stamped in the machine; and

Fig. 6 is a cross sectional view of a portion of the stamping head.

In one of its aspects the present invention consists in improvements in machines of the type disclosed in my prior Patent No. 1,137,103, granted April 27, 1915. Such details as are not fully shown in the accompanying drawings may correspond to those shown in said patent.

The frame of the machine comprises a box-shaped casting 2 having formed therein bearings for the main driving shaft 4 which is actuated by the pulley 6 from any suitable source of power. In the forward part of the frame is carried a work plate 76 and an oscillating head 34 carrying a series of stamping disks 66 is arranged to swing toward and from the work plate.

The driving shaft 4 carries a pinion 8 located within the machine frame and arranged to mesh with a larger pinion 10 loosely mounted on a counter shaft 12. The pinion 10 forms one part of the loose member of a roller clutch of which an eccentric 16 constitutes a part of the fast member. The clutch rollers are contained within a

cage or ring 14 having a tooth which is normally held by a spring latch mounted in one arm of a treadle lever 15 as shown in Fig. 2. When the treadle is depressed, the tooth on 5 the ring 14 is released and the clutch permitted to become engaged so that the eccentric 16 is rotated.

An eccentric strap 18 encircles the eccentric 16 and is provided with a tubular 10 stem or shank 20. Into the stem 20 extends the shank of a link member 22 pivotally connected to the rear end of the head 34 by a pin 28. The stem 20 of the eccentric strap is externally threaded to receive a nut 26 15 between which and a shoulder on the link member 22 is located a compression spring 24 tending normally to extend the connection. The action of the spring 24 may be varied by turning the nut 26 up or down 20 upon the stem 20. The link member 22 and the pin 28 are bored to receive an adjusting pin 30 which, at its inner end, is threaded into the eccentric strap 18. At its outer end the pin 30 is provided with a hand wheel 25 32 by turning which the connection between the eccentric and the link member may be reduced in length.

The head 34 is pivotally mounted upon a stationary journal shaft 36 extending 30 across the frame of the machine. It is oscillated by the eccentric 16 through the connections above described. Its point of nearest approach to the work table 76 may be regulated by adjusting the length of the 35 link connection through the medium of the hand wheel 32, while the degree of pressure may be regulated by adjustment of the nut 26.

The dies of the machine comprise two 40 series of disks 62—66 mounted upon a tubular journal 64 which extends across between the two sides of the head 34. The journal 64 is made tubular to receive an electric heating unit 60 to which current is supplied by the wires 61 shown in Fig. 1.

The left hand series of dies, as shown in Fig. 1, comprise a series of disks having radial projections upon the ends of which are formed the characters. These disks 50 serve to impress the case number upon the work and may be rotated to present any number of six digits, as the number 827319 shown in Fig. 5. At the rear of the disk 66 is secured a bar 72 having a guideway 55 for a series of sliding detents 74 normally pressed toward the disks by a series of springs 70. The detents 74 serve to hold each of the disks 66 yieldingly in position but permit the disks to be turned by the 60 operator when it is desired to set up a new case number.

The left hand series of dies comprise seven 65 disks having teeth formed on the periphery of each, which teeth carry the marking characters upon their ends. The two right hand

disks indicate the size of the shoe upper, the third disk bears the half size mark, and the four remaining disks of this series may indicate width or match mark. As shown in Fig. 5, the size indicated is 13 $\frac{1}{2}$, the width 70 2, and the match mark FKZ.

Above and at the rear of the disks 62 is provided a journal 56 upon which are mounted a series of idle pinions 58 meshing with the teeth of the stamping disks 75 62. These in turn mesh with the teeth of a series of pinions 40 mounted upon a journal member 38 in the upper part of the frame. That pinion 40 which corresponds to the one-half size disk 62 is provided with 80 a handle 42 by which it may be oscillated to move the one-half size die into or out of stamping position. The two right hand pinions 40 are connected respectively with the hand wheels 44 and 46 by means of concentrically disposed elongated hubs as shown in Fig. 6. The four left hand pinions 40 are similarly connected to the hand wheels 48, 50, 52 and 54 which are disposed on the left side of the head 34. Each of 85 the pinions is held yieldingly in position by a leaf spring 41 secured at its lower end to a bar 43 extending across between the sides of the head 34. The springs 41 yield readily to permit their respective pinions 90 to be turned through one or the other of hand wheels.

At the rear edge of the work plate 76 is provided a gage 78 having a downwardly extending shank which is received in a 100 socket piece 80 mounted in the machine frame for adjustment from front to rear. The head 34 is provided with forwardly projecting arms which engage the lower surface of the gage 78 and elevate the gage 105 against the tension of a spring 82 whenever the head 34 is elevated. The gage thus presents an effective surface to engage the edge of the work while the stamping head is elevated and is depressed out of the path 110 of the head when the stamping head is lowered. In order to prevent adjustment of the stamping head which would cause the dies to be forced into the work plate, there are provided a pair of adjustable stops 115 84 threaded into the ears 85 on the machine frame and arranged to be encountered by the arms of the head 34 in the downward movement of the latter. If the head is so adjusted that these stops are encountered, lost motion occurs between the head and its operating eccentric against the compression of the spring 24.

In operating the machine, the disks 66 are first set to give the required case number, and then by turning the hand wheels 44, 46, etc., and the handle 42, disks 62 are turned to present the required size, width and match mark. The work is then presented upon the table 76 and the machine 130

started, whereupon the stamping head is lowered and the shoe part is stamped or branded as indicated in Fig. 5.

Having thus described my invention, 5 what I claim as new and desire to secure by Letters Patent of the United States is:—

1. A stamping machine having, in combination, a head mounted for oscillation about a pivot, a series of adjustable dies and 10 corresponding manually operated adjusting devices mounted in the head opposite the pivot, the adjusting devices being at a distance from the dies, and actuating members connecting each die and its associated adjusting device and spacing them from one another.

2. A stamping machine having, in combination, a head mounted for oscillation about a pivot, a series of rotatable dies, a 20 corresponding series of manually operated adjusting devices mounted in the head opposite the pivot, the adjusting devices being movable about a parallel axis remote from the axis of the dies, and permanent actuating connections movable about an axis situated between each die and its associated adjusting device.

3. A stamping machine having, in combination, a movable head, a series of toothed 30 die carrying disks, a corresponding series of manually operated adjusting devices each including a toothed member, a toothed idler interposed between each die and the corresponding adjusting device, and a second series of disks concentric with the first and located opposite to certain of the adjusting devices.

4. A stamping machine having, in combination, a work support and stamping head 40 arranged for relative movement, said head including a tubular journal, an electric heating unit inclosed within the journal, a series of stamping disks rotatable upon the journal, an idler meshing with each disk, controlling means individual to each disk and being each arranged to be grasped by the hand of the operator and to act through the respective idlers, the portions grasped being situated on the opposite side of the idlers 50 from the disks.

5. A stamping machine having, in combination, a work support, an oscillatory head having a tubular journal, a stamping die adjustably mounted upon the journal, 55 means located within the journal for heating the die, an idler mounted in the head, and a hand operated device for adjusting the die located beyond the range of the heating means and acting through the idler.

6. A stamping machine having, in combination, a work support, and a stamping head having two series of adjustable stamping disks employed with different degrees of frequency, each disk of the more frequently employed series having an associated

hand operated adjusting device and the disks of the other series being constructed and arranged to be set by direct manipulation, certain of the adjusting devices being opposite the disks of the less frequently employed series.

7. A stamping machine having, in combination, a work support, a stamping head having two series of adjustable stamping disks, an idler meshing with each disk of one series, and a hand operated adjusting device acting through each idler.

8. A stamping machine having, in combination, a work support, a stamping head having two series of stamping disks all arranged in line with each other, separate hand operated adjusting devices for all disks of one series located upon the head and remote from their associated disks, and operating connections between said disks 85 and said adjusting devices.

9. In a stamping machine, a plurality of adjustable dies bearing characters used with different frequency, a readily accessible device for determining the position of a frequently used die, and a device for determining the position of a less frequently used die, the last-named device being confined to substantially the same space transversely of the machine as the die it controls.

10. In a stamping machine, a series of adjustable dies, devices situated at one side of the planes of the dies for respectively determining the position of said dies, a second series of dies used with less frequency than the first series, and devices for determining the position of the second series situated in the planes of the respective dies they control.

11. In a stamping machine, a plurality of series of adjustable dies, position-determining means for one series of dies at one side of said dies, and position-determining means for another series situated in alignment with the respective dies which they control, each die and its positioning means lying in a common plane independent of the planes of the associated dies.

12. A stamping machine having, in combination, a work support, a stamping head having two series of stamping disks, a sliding detent for each disk of one series, a hand operated adjusting device for each disk of the other series, and a spring detent acting upon each of said devices.

13. A stamping machine having, in combination, a work-support, an impression member movable into and out of coöperation with the support, an actuator, connections between the actuator and impression member including a link having sections movable relatively to one another, and means constructed and arranged to adjust the relation between the sections and extending to the end of the link.

14. A stamping machine having, in combination, a work support, a movable carrier member, a link pivoted thereto, an actuator for the carrier, and means extending 5 through the pivot of the link and into the actuator for adjusting the relation of the carrier and actuator.

15. A stamping machine having, in combination, a work support, a pivotally mounted carrier member, an operating eccentric, 10 an eccentric strap having a shank, a link having a telescopic connection with said shank, a spring tending normally to extend said connection, and adjusting means for

shortening said connection in opposition to 15 the spring.

16. In a stamping machine, a plurality of series of adjustable dies, said series extending laterally of the machine, position-determining means for one series of dies out 20 of alinement therewith longitudinally of the machine, and position-determining means for another series of dies situated in longitudinal alinement therewith.

In testimony whereof I have signed my 25 name to this specification.

HENRY W. WINTER.
